Des. 193,401
Patented Aug. 14, 1962

193,401

SHUTTLECOCK

William C. Carlton, 14 Herbert Road, Hornchurch,
Essex, England

Filed Feb. 14, 1962, Ser. No. 68,826

Term of patent 14 years

(Cl. D34—5)

FIG. 1.

FIG. 2.

FIG. 3.

FIG. 4.

FIG. 5.

FIGURE 1 is an isometric view of a shuttlecock showing my new design;

FIGURE 2 is a side elevation of the new design;

FIGURE 3 is a plan view of the new design;

FIGURE 4 is a horizontal section through the shuttlecock at 4—4 in FIGURE 2; and

FIGURE 5 is a fragmentary vertical section through the shuttlecock at 5—5 in FIGURE 2.

I claim:

The ornamental design for a shuttlecock, as shown.
